UNITED STATES PATENT OFFICE.

JOSEPH CONLEY, OF ANADARKO, OKLAHOMA.

INCINERATOR.

1,093,829.

Specification of Letters Patent. Patented Apr. 21, 1914.

Application filed June 26, 1913. Serial No. 775,994.

To all whom it may concern:

Be it known that I, JOSEPH CONLEY, a citizen of the United States, residing at Anadarko, in the county of Caddo and State 5 of Oklahoma, have invented certain new and useful Improvements in Incinerators, of which the following is a specification.

My invention relates to certain new and useful improvements in incinerators, and 10 the object of my invention is to provide an incinerator built on the unit system, and with one or more furnaces in each unit, and all connected to a single stack.

A further object of my invention is to 15 provide an incinerator of this type which will give complete combustion of the gases generated, and by which the cost per ton of incinerating garbage and other refuse is materially reduced.

20 A further object of my invention is to produce an incinerator which is comparatively cheap in its construction, and one which is not likely to get out of repair, and which is capable of being operated under 25 the various conditions necessary.

With the foregoing and other objects in view my invention consists in certain constructions, combinations and arrangements of parts, the preferred form of which will 30 be first described in connection with the accompanying drawings, and then the invention particularly pointed out in the appended claims.

Referring to the drawings wherein the 35 same part is designated by the same reference numeral wherever it occurs, Figure 1 is a vertical section through an incinerating plant constructed in accordance with my invention, and Fig. 2 is a horizontal section 40 through the construction shown in Fig. 1.

5 designates the stack which may be of any desired height, and which may be provided at its base with a grate 6, on which a fire may be maintained when necessary, to 45 complete the combustion of the gases. I also provide a stoke hole 6' for the fire in the grate 6.

7 designates a chamber into which all the furnaces empty, the chamber being connected to the stack by a flue 8. If desired a boiler 9 may be inserted in the flue 8 to utilize a portion of the heat passing therethrough, and which would otherwise be wasted.

55 10 and 11 designate a pair of furnaces located on one side of the chamber 7, and 12

and 13 a second pair of furnaces located on the other side of the chamber 7. Each of these furnaces comprises a grate 14, stoking openings 15, a partition wall 16 which divides the furnace into two chambers, comprising the combustion chamber 17 and a secondary chamber 18. The chambers 17 and 18 are connected through the partition 16 by a pair of flues 19, 20, the flue 19 being 60 provided with a damper 21 and the flue 20 with a damper 22.

23 is the garbage or refuse supporting bridge onto which garbage or other refuse may be dumped through a man hole 24 in 70 the top of the furnace, said manhole being provided with a cover 25. The bridge 23 is inclined from the rear toward the front of the furnace, as shown.

Between the rear wall of the secondary 75 chamber 18 and the chamber 7 is a partition wall 26, provided with flue openings 27, 28 therein, the flue opening 27 being provided with a damper 29, and the flue opening 28 with a damper 30. These two openings extend through the partition wall 26 above the level of the floor 31 of the chamber 7. I also provide, below the floor 31, a third flue opening 32, having a damper 33 therein. The floor 31 is provided at its front 85 portion with a grate 34.

In operation as many of the furnaces 10, 11, 12 and 13 are started as may be necessary, and a charge of garbage or other refuse is dumped through the manhole 24 onto 90 the inclined bridge 23. The damper 22 may now be closed, the damper 33 opened, while the dampers 29 and 30 remain closed. The products of combustion from the grates will now pass over the garbage on the 95 bridge into the secondary chamber 18, and thence through the flue 32, through the grate bars 34, on which a fire is also built, and thus to the stack. This will insure the complete combustion of all the gases. After 100 the refuse has become dried out and partially incinerated upon the bridge it can, through the openings 35 and 36, be brought down onto the grate section 14, and the solid sections 37, 38, on each side of the 105 grate section. The damper 21 can now be closed, the damper 22 opened, when the gas will pass directly to the stack through the grate 34, without however passing over the bridge 23. The new charge of refuse can 110 now be dumped in through the manhole 24 upon the bridge 23, and the heat of the burn-

ing refuse on the grates utilized to assist in the drying out of the fresh charge of garbage. If no fire is used on the grate 34, then the damper 33 can be closed, and the damper 29 or 30 opened, depending upon whether the damper 21 or 22 is open. The chamber 7 into which all the furnaces empty is heated to a very high heat, and as a consequence it can be used for the cremation of dead animals, and it is desirable, when it is being used as a crematory, that oil burners 39 be turned on to further increase the heat in the chamber 7.

From the foregoing it will be seen that a plant constructed in accordance with this invention can be economically operated for varying amounts of refuse to be disposed of by using only a portion of the furnaces, and that the wet garbage is not dumped directly onto the furnace fires and consequently does not smother them, as would be the case were the garbage charged directly onto the fire. Furthermore by the dampers and flues which I have provided it is possible to handle the gases given off by the refuse in such a way that they will be entirely consumed before passing out of the stack.

I am aware that considerable variation is possible in the details of construction herein shown and described, without departing from the spirit of my invention, and I do not intend to limit myself thereto, except as pointed out in the following claims, in which it is my intention to claim all the novelty inherent in the structure shown and described as broadly as the state of the art will permit.

Having thus described my invention what I claim as new and desire to secure by Letters Patent is:

1. In an incinerator the combination with a stack, a chamber connected with the stack, a plurality of furnaces each of which is connected to the chamber by a plurality of flues, each provided with a damper, each furnace comprising a main chamber and a secondary chamber, a plurality of flues, each provided with a damper connecting the main and secondary chambers, a bridge located in the main chamber between the flues, and a grate located beneath the bridge.

2. In an incinerator the combination with a stack, a chamber connected with the stack, a plurality of furnaces, each of which is connected to the chamber by a plurality of flues, each provided with a damper, each furnace comprising a main chamber and a secondary chamber, a plurality of flues each provided with a damper connecting the main and secondary chambers, a bridge located in the main chamber between the flues, a grate located beneath the bridge, and a second grate located in the first-mentioned chamber with one of the flues from the secondary chamber connected to said first-mentioned chamber located beneath the last mentioned grate.

In testimony whereof I affix my signature in presence of two witnesses.

JOSEPH CONLEY.
